[57] CLAIM

The ornamental design for a spiral vaso-occlusion coil, as shown and described.

DESCRIPTION

FIG. 1 is a perspective view of a first embodiment of the spiral vaso-occlusion coil embodying my design;

FIG. 2 is a top plan view thereof;

FIG. 3 is a right side view thereof;

FIG. 4 is a left side view thereof;

FIG. 5 is a front view thereof;

FIG. 6 is a rear view thereof;

FIG. 7 is a bottom view thereof;

FIG. 8 is a perspective view of a second embodiment of the spiral vaso-occlusion coil embodying my design;

FIG. 9 is a top plan view thereof;

FIG. 10 is a right side view thereof;

FIG. 11 is a left side view thereof;

FIG. 12 is a front view thereof;

FIG. 13 is a rear view thereof;

FIG. 14 is a bottom view thereof;

FIG. 15 is a perspective view of a third embodiment of the spiral vaso-occlusion coil embodying my design;

FIG. 16 is a top plan view thereof;

FIG. 17 is a right side view thereof;

FIG. 18 is a left side view thereof;

FIG. 19 is a front view thereof;

FIG. 20 is a rear view thereof; and,

FIG. 21 is a bottom view thereof.
